CLAIM

The ornamental design for an open web dissymmetric beam, as shown and described.

DESCRIPTION

FIG. 1 is a top perspective view of our design for an open web dissymmetric beam;

FIG. 2 is a view in elevation from either side of the open web dissymmetric beam shown in FIG. 1;

FIG. 3 is a top plan view of the open web dissymmetric beam shown in FIG. 2;

FIG. 4 is a bottom plan view of the open web dissymmetric beam shown in FIG. 2; and,

FIG. 5 is a view in elevation from either end of the open web dissymmetric beam of the present design.

The open web dissymmetric beam in broken is the center indicating indefinite length.
